UNITED STATES PATENT OFFICE.

ARTHUR T. BOLLAND, OF OAK PARK, AND JOHN GALL AND JOHN F. DESTER, OF CHICAGO,
ILLINOIS.

WINDOW-CLEANING DEVICE.

No. 914,106.

Specification of Letters Patent.

Patented March 2, 1909.

Application filed September 1, 1908. Serial No. 451,152.

To all whom it may concern:

Be it known that we, ARTHUR T. BOLLAND, a citizen of the United States, residing in Oak Park, county of Cook, and State of Illinois, and JOHN GALL and JOHN F. DESTER, both citizens of the United States, and both residing in Chicago, in the county of Cook and State of Illinois, have invented certain new and useful Improvements in Window-Cleaning Devices, of which the following is a specification.

This invention is in the form of a squeegee device which is permanently attached to the window frame of the window upon which it is intended to act; and the object of the invention is to permit the outside of such window to be cleaned by manipulation from the inside without the necessity for opening the window, and without the necessity of standing outside of the window during the cleaning operation.

The invention is particularly applicable to the front windows of street cars or electric cars generally, through which the motorman commands a view of the track ahead. In rainy or snowy weather it frequently happens that such windows are obscured by the accumulation of snow or moisture on the window, so that it becomes difficult, if not impossible, for the motorman to view the track ahead, thereby endangering the safety of the passengers. It is difficult, if not an impossibility, for the motorman to clean the outside of the window from within the car while at high speed, and frequent cleaning of the window, while the car is stopped is not feasible. The present invention permits the window to be instantly cleaned at frequent intervals by the manipulation of a handle within easy reach of the operator, so that the window can be cleaned as often as required without materially interfering with the motorman's manipulation of the devices controlling the car.

Although the invention is peculiarly adapted for use on trolley cars or other electric cars it can be used on automobiles, or windows generally, on which it is desired to secure similar results.

The invention consists in the features of construction and combination of parts as hereinafter described and claimed.

In the drawings Figure 1 is a face view of the outside of the window, showing the device of the present invention in elevation;

Fig. 2 a sectional plan view of the same; Fig. 3 an enlarged cross sectional view of the squeegee frame and squeegee; Figs. 4 and 5 two details showing the squeegee in different positions of adjustment; and Fig. 6 a detail of the housing.

The device is applied to a window frame having side rails 6, a top rail 7, and a bottom or base rail 8 of the usual character and of any desired size or proportions. The side rails, adjacent the window pane 9, are provided with vertical slots 10, which latter permit movement of the movable portions of the device. Cleaning is performed by means of a rubber squeegee 12, which is set at an oblique angle with respect to the outer face of the window pane and is adapted to clean the same by a downward movement. The squeegee strip is clamped within a transversely extending frame 13 which is in the form of a flat plate provided with a flange 14 at its outer edge. The rubber is held in position within the frame by means of a clamping bar 15 secured to the frame by means of screws 16, or in any other suitable manner. The frame lies at an oblique angle with respect to the outer surface of the window pane, and the upper inner edge of the rubber strip forming the squeegee projects from the frame a sufficient distance to engage the glass of a window pane. The frame 13 is provided, near its ends, with a pair of depending fingers 16^a, which are pivoted, near the centers, inside of ears 17, which outwardly project from the inner ends of T shaped bracket plates 18, on opposite sides of the window frame as a whole. The T bracket plates 18, on the outside of the window frame, coöperate with similar T shaped bracket plates 18^a on the inside of the window frame, which bracket plates are spaced and connected by means of spacing blocks 19, to which the bracket plates are secured by means of screws 20. Between the ends of the bracket plates are interposed rollers 21, which engage the sides of vertical slots and serve to facilitate the travel of the brackets. The bracket plates 18^a are connected by means of a transversely extending handle bar 22, on the inside of the window pane, in the center of which handle bar is a handle 23, which permits vertical manipulation of the device as a whole. The bar 22, on the inside of the window, coöperates with a connecting bar 24 similarly positioned on

the outside of the window frame and connecting the bracket plates 18, best shown in Fig. 3. The connecting bar 24, at its ends, is provided with recesses 25, into which are entered springs 26 which exert an outward pressure against the ends of the fingers 16^a, which spring pressure serves to bring the edge of the squeegee into close contact with the face of the window pane. The springs are held in place by means of inwardly projecting screws 27, a nut or washer 28 being interposed to permit adjustment of the spring pressure. In order to throw the squeegee out of contact with the window pane on the upward stroke of the handle, cam bars 29, one on each side, are provided, which are entered through slots 29^a cut in the inner faces of the inwardly extending portions of the T bracket plates, the upper ends of which cam bars are beveled, as shown in Figs. 4 and 5, and are adapted to underlie a pair of outwardly projecting lugs 30 on the ends of the squeegee clamping bar 15. The cam bars are provided with recesses 31, which afford shoulders 32 and 33, for limiting their movements; and the bars are adapted to be thrown from one position to another by contact with upper and lower stops 33^a and 34, which are formed on inner guide plates 35 which lie inside of the vertical slots on each side of the window and against which the cam bars abut, being held between said plates and the slotted portion of the T brackets. The inner guide plates are supplemented by outer guide plates 36, positioned outside of the slots, which plates afford metallic surfaces for preventing wear during the movements of the squeegee frame. In order to provide against the ingress of moisture, dust, or other foreign substances through the slots, the latter are protected on the outside by means of housings 37, each of which is provided, along its inner edge, with a lip or flange 38 provided, near its lower end, with a recess 39, which is beveled or rounded at its upper end 40, and which serves to afford a clearance for the bracket plates when the squeegee is in its lowermost position. The housing is secured to a plate 41 by means of a hinge 42 provided with a spring 43 adapted to hold the flanged edge of the housing into close contact with the inner guide plate, save only when the device is being raised and lowered.

If, for any reason, it is desired to provide a squeegee for the inside of the window as well as the outside, the squeegee frame and mechanism heretofore described can, without change or modification, be duplicated on the inside of the window.

In use, when it is desired to clean a window of snow or sleet, the handle will be raised with sufficient force to bring the upper ends of the cam bars into sharp contact with the upper stops 33^a which movement serves to throw

down the cam bars into their lowermost position, thereby releasing the lugs 30 from the position shown in Fig. 4, and allowing them to fall in the position shown in Fig. 5, which release permits the springs 26 acting against the outer or free ends of the fingers 16^a to exert a pressure which will hold the edge of the squeegee into close engagement with the surface of the window as the handle on the inside of the window is lowered. The oblique angle of the squeegee, with respect to the window, causes water, snow or sleet to be carried down by the squeegee without difficulty until the lowermost position is reached, at which point the handle is moved with sufficient suddenness to bring the cam bars into sharp contact with the lower stops 34, which throws the bars from the position shown in Fig. 5 to the position shown in Fig. 4, thereby again elevating the squeegee frame and permitting further manipulation of the squeegee. By providing the stop and cam mechanism heretofore described the squeegee can be easily raised, which would be difficult or impossible if the angularly disposed edge of the squeegee were maintained in contact with the window pane during the upward thrust. During the movements of the squeegee the housings will be raised against the pressure of the springs so that the movable portions of the mechanism can pass under the edges of the housings without exposing the slots, and without permitting ingress of water from without.

In the specification and claims where we use the term squeegee, it will be understood that such term is not to be strictly limited to a strip of rubber, but contemplates any suitable substance adapted to be manipulated in the manner specified, whereby the window can be wiped and cleaned.

What we claim as new and desire to secure by Letters Patent is:

1. The combination of a window frame provided with parallel slots forming guideways, brackets moving within the slots, a squeegee frame carried by the brackets and carrying a squeegee adapted to engage one side of the window, a handle on the opposite side of the window connected with the brackets, and springs for holding the squeegee under pressure against the window, substantially as described.

2. The combination of a window frame provided with parallel slots forming guideways, brackets moving within the slots, a squeegee frame carried by the brackets and carrying a squeegee adapted to engage one side of the window, a handle on the opposite side of the window connected with the brackets, springs for holding the squeegee under pressure against the window, and means for automatically throwing the squeegee out of contact with the window, substantially as described.

3. The combination of a window frame provided with parallel slots forming guideways, brackets moving within the slots, a squeegee frame carried by the brackets and carrying a squeegee adapted to engage one side of the window, a handle on the opposite side of the window connected with the brackets, springs for holding the squeegee under pressure against the window, a slideable cam bar carried by one of the brackets and adapted to throw the squeegee out of engagement with the window, and stops adapted to be engaged by the slideable cam bar for moving the same to different positions of adjustment, substantially as described.

4. The combination of a window frame provided with parallel slots forming guideways, brackets movable within the slots, each of the brackets comprising a pair of connected bracket plates inwardly extending toward the window, a handle bar connecting the bracket plates on one side of the window, a bar connecting the brackets on the opposite side of the window, a squeegee frame pivoted on the side of the window opposite the handle, and a squeegee carried within the squeegee frame, substantially as described.

5. The combination of a window frame provided with parallel slots forming guideways, brackets movable within the slots, each of the brackets comprising a pair of connected bracket plates inwardly extending toward the window, a handle bar connecting the bracket plates on one side of the window, a bar connecting the brackets on the opposite side of the window, a squeegee frame pivoted on the side of the window opposite the handle, a squeegee carried within the squeegee frame, and springs adapted to hold the squeegee in close engagement with the window, substantially as described.

6. The combination of a window frame provided with parallel slots forming guideways, brackets movable within the slots, each of the brackets comprising a pair of connected bracket plates inwardly extending toward the window, a handle bar connecting the bracket plates on one side of the window, a bar connecting the brackets on the opposite side of the window, a squeegee frame pivoted on the side of the window opposite the handle, a squeegee carried

within the squeegee frame, springs adapted to hold the squeegee in close engagement with the window, a cam bar engaging the end of the squeegee frame and adapted, when moved to one position, to throw the squeegee out of contact with the window, and stops near the ends of the guideways and located in position to be engaged by the cam bar to throw the bar to different positions of adjustment, substantially as described.

7. The combination of a window frame provided with parallel slots forming guideways, brackets slideable within the guideways and each comprising a pair of connected bracket plates, a handle bar connected with the bracket plates on one side of the window, a bar connecting the bracket plates on the other side of the window, a squeegee frame, a squeegee carried by the frame, fingers rearwardly projecting from the squeegee frame and pivoted to the bracket plates on the side of the window opposite to the handle, and springs engaging the free ends of the fingers and adapted to exert a pressure thereon to hold the squeegee in contact with the window, substantially as described.

8. The combination of a window frame provided with parallel slots forming guideways, brackets slideable within the guideways and each comprising a pair of connected bracket plates, a handle bar connected with the bracket plates on one side of the window, a bar connecting the bracket plates on the other side of the window, a squeegee frame, a squeegee carried by the frame, fingers rearwardly projecting from the squeegee frame and pivoted to the bracket plates on the side of the window opposite to the handle, springs engaging the free ends of the fingers and adapted to exert a pressure thereon to hold the squeegee in contact with the window, and automatic means for retracting the squeegee frame to throw the squeegee out of contact with the window, substantially as described.
